corporation of Virginia

Application July 29, 1942, Serial No. 452,713

8 Claims. (Cl. 158—42.4)

1

My invention relates to fuel feeding systems and is more particularly concerned with the gasoline supply line for an internal combustion heater installed in an airplane.

In modern airplane practice, it is common to locate internal combustion heaters in various parts of the airplane fuselage and to supply these heaters with gasoline from the main fuel tanks of the airplane. In many instances the heaters are located at considerable distances from the fuel tanks which form their source of supply and there are long gasoline feed lines connecting the fuel tanks and heaters. In military aircraft, these gasoline feed lines may be damaged by enemy action and some of the gasoline therein may leak into the cabin.

An object of my invention is to provide a new and improved fuel feeding system which will reduce the possibility of gasoline leakage from a broken feed line.

Another object of my invention is to provide a fuel feeding system for an internal combustion heater or similar device and wherein the fuel feeding pipes or conduits will be drained of fuel except when the heater or similar device is in actual operation.

Another object of my invention is to provide a fuel feeding system of the kind hereinabove indicated which may be easily installed and which will not increase the weight over existing fuel feeding systems.

Another object of my invention is to provide a new and improved fuel feeding system which can be easily embodied in present fuel feeding systems by a few simple modifications thereof.

Other objects and advantages will become apparent as the description proceeds.

In the drawings, Fig. 1 is a diagrammatic representation of a part of an airplane having a preferred embodiment of my invention applied thereto, and Fig. 2 is a sectional view on an enlarged scale of the solenoid valve of Fig. 1.

In the drawing I have indicated an airplane having a fuselage 10 and a wing 12 provided with one or more main fuel tanks 14 for supplying gasoline to the engine or engines which propel the airplane. The fuel tank 14 is also utilized as a source of fuel for one or more internal combustion heaters 16 which may be located at a lower level and at relatively great distances from the fuel tank 14. The internal combustion heater 16 may be of any conventional or usual type and is illustrated as being located in a duct 18 through which air is forced by a blower 20 driven by any suitable means. An air scoop or ram may be

2

used in place of the blower in many installations.

The air discharged by the blower 20 flows over the heat exchange fins of the heater 16 and thence through the duct 18 to the cabin or other space which it is desired to heat. It will be understood by those skilled in the art that the internal combustion heater 16 may be provided with the usual controls and may be of any size necessary to accomplish its desired purpose. The 10 particular location of the heater 16 is for illustrative purposes only and the location of the heater or heaters will depend upon the type of airplane and the number of heaters installed therein.

15 Fuel is withdrawn from the tank 14 by a fuel pump P discharging into a pipe 22 leading to a carburetor 24 which supplies the heater 16 with a combustible mixture of gasoline and air. The carburetor 24 receives its supply of air through 20 an inlet 26 connected to the discharge side of the blower 20 and diverting a small portion of the air discharged by this blower to the carburetor inlet. The combustible mixture formed in the carburetor 20 passes through inlet pipe 28 to 25 heater 16 where it is burned and the products of combustion formed in the heater are discharged through an exhaust pipe 30 having an outlet end 32 preferably, but not necessarily, arranged to create a suction in the heater 16.

30 In the normal operation of the apparatus, the flow of gasoline to the heater 16 is controlled by the solenoid valve 34 located in the pipe 22. This valve is connected by wire 36 and switch 38 to a battery 40 illustrated as grounded at 42. In lieu 35 of the battery 40, any other suitable source of electrical current may be utilized.

The solenoid valve 34, as shown more clearly in Fig. 2, is of the type wherein the valve member 33 is normally urged by a spring 35 towards closed position and wherein this valve member is held in open position against the force of this spring only while the solenoid 39, 41 is energized. The valve 34 has an air inlet 37 which is closed when the valve member is in open position. When 40 the valve member is in closed position, the inlet 37 is in communication with that part of the pipe 22 which connects the valve 34 with the carburetor 20, but is cut off from communication with that part of pipe 22 which connects the valve 34 and pump P.

45 I have also shown an emergency valve 44 as being located in the pipe 22 adjacent the carburetor 24. The valve 44 is also a solenoid valve and has a valve member biased toward open position by the usual spring. The valve member is 50

held in closed position only while the solenoid is energized. The valve 44 has no air inlet corresponding to the inlet 37 of valve 34. A wire 46 connects solenoid valve 44 to an overheat switch 48 which is normally open but which closes when the air in that part of duct 18 adjacent this switch reaches an abnormally high temperature.

The overheat switch 48 and emergency solenoid valve 44 may be supplied with current from any suitable source. In the embodiment illustrated in the drawing, I have shown this source as a battery 40 which is connected to the overheat switch 48 through wire 50 and switch 38. It will be understood that the heater 16 is provided with the usual ignition circuit and controls therefor and may be provided with any other usual or suitable controls for regulating the heat output or other operating characteristics of the heater.

When the heater 16 is not operating, that part of pipe 22 which connects valve 34 with carburetor 24 is in open communication with air inlet 37 and is entirely empty of gasoline. If it is desired to start the heater, switch 38 is closed, thereby energizing the solenoid in the solenoid valve 34. Emergency valve 44 remains open. Simultaneously, or substantially so, blower 20 is started and the igniting means of the heater 16 is put in condition to ignite any combustible mixture supplied thereto.

In the embodiment shown in the drawing, I have illustrated the fuel pump P as being an electric fuel pump which is supplied with current through a wire 52 connected to battery 40 through switch 38 so that the pump P will be energized simultaneously with the opening of solenoid valve 34. Where the pump P is utilized to supply fuel to other heaters or other equipment, additional controls will, of course, be provided so that the operation of the pump P will conform to the needs of all of the equipment to which it supplies fuel. The pump P need not be an electrically operated pump but may be a mechanically driven pump or any other suitable means for withdrawing fuel from tank 14 and forcing the fuel through piping to the point or points where it is utilized.

Energization of the solenoid in solenoid valve 34 opens this valve, thereby providing free communication between the portions of pipe 22 on opposite sides of this valve and also closing the air inlet 37. Fuel discharged by the pump P flows rapidly into the pipe 22 and in a very brief interval completely fills this pipe and reaches the carburetor 24. In the meantime, air in pipe 22 has been sucked into carburetor 24 and discharged through heater 16, which, of course, does not start to operate until supplied with a combustible mixture.

When the gasoline flowing into pipe 22 reaches carburetor 24, this gasoline is mixed with air and the combustible mixture thus formed flows through pipe 28 to heater 16, where it is ignited and gives up its heated air forced over the heater by blower 20. The products of combustion from the heater are discharged to atmosphere through pipe 30. The heated air in the duct 18 is utilized to heat a cabin or other space in the airplane or for any other desired purpose and any usual or suitable control means may be provided to regulate the temperature of the heated air.

If the air in duct 18 adjacent overheat switch 48 reaches a predetermined abnormally high temperature, switch 48 closes. This energizes the solenoid in emergency valve 44 and causes

this valve to cut off the supply of fuel to the carburetor 24 and heater 16. As soon as the temperature adjacent the switch 48 has dropped to a safe value, switch 48 opens and emergency valve 44 again assumes its normally open position. Fuel again flows to carburetor 24 and is ignited in heater 16, which assumes its normal operation.

When it is desired to shut off the heater 16, switch 38 is moved to open position. This de-
10 energizes the solenoid in valve 34 and permits the valve member therein to cut off communication between the pump P and that part of pipe 22 which connects valve 34 with carburetor 24. This shift in the valve member of valve 34 con-
15 nects inlet 37 with that part of pipe 22 which connects this valve with carburetor 24 and heater 16 continues to operate until all fuel has been withdrawn from this part of pipe 22.

Heater 16 thereupon ceases to operate and
20 blower 20 should then be stopped through any suitable manual or automatic control means, as for example, when the blower 20 is electric motor driven, a temperature responsive switch in the motor circuit may be located so that it opens whenever the heater becomes cold. Thus the blower 20 may continue to operate for a brief period after the flow of combustible mixture to the heater 16 has ceased in order to dissipate heat stored up in the body of the heater itself.
25
30 As long as the switch 38 remains open, that part of the fuel supply line which lies between valve 34 and heater 16 contains no gasoline but is filled with air under atmospheric pressure. Any damage to this part of the fuel supply line during
35 this period would not result in leakage of gasoline. It is only during actual operation of the heater that the main portion of the fuel supply line for the heater contains gasoline.

In the embodiment of my invention selected for
40 purposes of illustration, the carburetor is sup-
plied with air from the blower 20 and this blower is used to force air through the duct 18. In some installations, either or both of these functions
45 may be performed by a ram or rams. Since there will ordinarily be but little suction at the outlet of the fuel supply line 22, this line should be located so as to facilitate gravity flow of the fuel from the valve 34 to the carburetor whenever the
50 valve 34 is closed.

An important feature of my invention lies in the fact that my new and improved fuel feeding system is simple and easily installed and adds no weight to the fuel feeding systems now in use. Furthermore, the fuel feeding systems now in use
55 can easily be converted to embody my invention and thereby materially reduce the fire hazard in airplanes utilizing these fuel feeding systems.

The embodiment shown in the drawing is il-
lustrative only and my invention is not limited to the details shown and described but is susceptible to numerous variations and modifications com-
ing within the scope of the appended claims.

I claim:

1. A fuel feeding system for supplying an internal combustion heater of an airplane with fuel from a fuel tank located at a distance from the heater comprising a relatively long pipe connecting said tank and heater, a valve between said tank and pipe and adjacent the tank for controlling com-
70 munication between said tank and pipe, control means for opening and closing said valve, and an air inlet for said pipe controlled by said valve, said air inlet being above said pipe.

2. A fuel feeding system for supplying an internal combustion heater of an airplane with

fuel from a source located at a substantial distance from the heater, comprising a relatively long pipe, an inlet valve for said pipe controlling communication between said pipe and said source of fuel supply, and vent means controlling communication between said pipe and atmosphere automatically to admit air to said pipe when said valve is closed and to exclude air from said pipe when said valve is open, said vent means communicating with atmosphere at a point higher than any part of said pipe.

3. A fuel feeding system for supply an internal combustion heater of an airplane with fuel from a source located at a substantial distance from the heater, comprising a relatively long pipe connecting said heater with said source of fuel supply, a valve adjacent the inlet end of said pipe for controlling flow of fuel therethrough, vent means above said pipe for admitting air to said pipe when said valve is closed and for excluding air from said pipe when said valve is open, and a common control means for said valve and vent means.

4. In a fuel feed system for supplying an internal combustion heater of an airplane with fuel from a source located at a substantial distance from the heater, comprising a relatively long pipe connecting said heater with said source of fuel, a valve member adjacent the said source at the inlet end of said pipe for controlling flow therethrough, means interposed between said valve member and heater and adjacent said valve member for admitting air to said pipe when said valve member is in closed position and for excluding air from said pipe when said valve member is in open position, and a control circuit for said last-named means and valve member, said circuit including a switch for closing said valve member prior to stoppage of said heater due to lack of fuel.

5. A fuel feeding system for supplying an internal combustion heater of an airplane with fuel from a fuel tank remote from the heater, comprising a pipe of substantial length extending through most of the distance from said tank to said heater, a fuel valve controlling communication between said tank and said pipe and located adjacent the tank, and vent means which is closed when the valve is opened and which is opened by the closing of the valve, said vent means being in said pipe adjacent said valve and admitting atmosphere at a point higher than any part of said pipe.

6. In a fuel feeding system as defined in claim 5, electrical means operative to hold said valve open when energized, and an electrically driven pump interposed between the tank and the valve, and connected in the same circuit with said valve, and switch means controlling said circuit.

7. In a fuel feeding system as defined in claim 5, an electric circuit which includes means operative to hold the fuel valve open when the circuit is closed and to allow said valve to close when said circuit is opened, a biased and normally open emergency valve in said pipe adjacent the heater, electrically operable means for closing said emergency valve, an actuating circuit therefor and a common control switch for both circuits, whereby the opening of said switch causes the fuel valve to close and insures the opening of the emergency valve and vents the said pipe to atmosphere.

8. In a fuel feeding system as defined in claim 5, an electric circuit which includes means operative to hold the fuel valve open when the circuit is closed and to allow said valve to close when said circuit is opened, a biased and normally open emergency valve in said pipe adjacent the heater, electrically operable means for closing said emergency valve, an actuating circuit therefor including a thermally operable switch which closes said circuit in response to a predetermined temperature produced by the heater, and a common control switch for both circuits operable at will, whereby the opening of said switch causes the fuel valve to close and causes the emergency valve to open if already closed by said thermal switch and vents the said pipe to atmosphere.
